IGNITION COIL

Herman L. Hartzell and Dalphin L. Hittle, Anderson, Ind., assignors to General Motors Corporation, Detroit, Mich., a corporation of Delaware

Application September 28, 1939, Serial No. 296,906

7 Claims. (Cl. 175—361)

This invention relates to ignition coils for automotive use, and is concerned particularly with oil or wax impregnated coils, or those coil bodies that are rigidly secured within a casing that is hermetically sealed to insure against fluid flow through any of the junctures of the enclosing casing or through any of the circuit terminal mountings. A form of coil to which the present invention relates is disclosed in the copending application of Herman L. Hartzell, Ser. No. 10 296,904 filed September 28, 1939.

It is an object of the present invention to provide certain improvements in the type of coil disclosed in the Hartzell application referred to, with the aim to reduce the cost of manufacture of coils having fluid tight enclosures, in which the coil body can be properly located so that the impregnant can reach all parts of the enclosure and the voids of the assembly.

A further object of the invention is to improve the means for providing a fluid tight seal between the coil container of thin sheet metal and the high tension terminal of porcelain.

Further objects and advantages of the present invention will be apparent from the following description, reference being had to the accompanying drawing wherein a preferred embodiment of the present invention is clearly shown.

In the drawing:

Fig. 1 is a view partly in elevation and partly in section, illustrating the instant invention substantially as indicated by the line and arrows 1—1 of Fig. 2.

Fig. 1A is a sectional detail of seam construction.

Fig. 2 is a top plan view of the ignition coil substantially as indicated by the arrow 2 of Fig. 1.

Fig. 3 is a transverse sectional view substantially as indicated by the line and arrows 3—3 of Fig. 1, it showing a plan of the core cup.

Fig. 4 is a transverse sectional view substantially as indicated by the line and arrows 4—4 of Fig. 1, and showing the winding locator in plan.

Fig. 5 is an enlarged detail view in section showing the construction of one of the primary terminals.

Fig. 6 is a similar type view showing the details of construction of the high tension terminal.

With specific reference to the drawing, 10 refers to a sheet metal coil case having a longitudinal lock seam 12 (Fig. 4) and being closed at each end by members 14 and 16. Member 14 supports circuit terminals as 18 and 20. End member 16 supports terminal 22. Enclosed with-

5 in the casing is a coil assembly unit 24, including a bundle of core wires 26 supporting a secondary winding 27 and about which is wound a primary winding 28. A lead from the inside end of the secondary winding 27 is tucked in between the core wires 26 in the usual manner, and the outside secondary winding lead and the inside primary winding lead are twisted together and fastened by a clip 30, from which a lead 32 makes connection with the primary terminal 18. The outside end of the primary winding is joined to a lead 34 by a clip 35, and this lead is secured to the other primary terminal 20. The end members 14 and 16 may be secured to the ends 15 of the case member 10, in any desired manner that will effect a sealed juncture, but it is preferred that this be accomplished by a double rolled seam incorporating a gasket 37 (Fig. 1A) of oil and heat resistant material, such as rubber or latex bonded cork. Seam junctures of that type are indicated at 36 and 38, by which the end members 14 and 16 are each secured to one end of the case 10. Contributing to that type of seam each of the end members initially 20 has an open rolled edge 40 (Fig. 6), that is finally interlocked with the end of the case 10.

The specific construction of the end member 16 is illustrated in Fig. 6, where it will be seen that the member has a raised rim 42 bounding 30 which is the open roll 40. Centrally of member 16 there is a depressed portion 44 that is apertured at 46 for reception of a high tension terminal insulator 48 having a flange 50. The insulator 48 is of porcelain or like material and terminates inside of the member 16 with a cylindrical portion 52, there being a longitudinal bore or passage 54 therethrough, which is reduced at 56, the outside end. A compressible gasket 58 of oil and heat resisting characteristics is disposed over the cylindrical portion 52 of the insulator and occupies a position between the flange 50 and the depressed portion 44 of the member 16. Then a ring 60 of porcelain or the like is placed over the cylindrical portion 52 of the insulator which it closely fits and is pressed against the inside surface or the bottom wall of the depression 44. The outside diameter of the part 52 is of a dimension to closely fit the apertures of the member 16, the gasket 58 and the ring 60.

These parts 16, 48 and 60 are held in fluid tight relation by means of a terminal assembly consisting of a tubular member 62 in the outside end of which is secured a hollow terminal tip 64, which may be accomplished by hydrogen-

brazing or the like. The tip 64 has a longitudinal bore 66 and an external annular shoulder or flange 68 which fits against the end of the tube 62 where it is secured in fluid tight relation by the brazing or otherwise. This terminal construction is inserted from the outside end through the bore 56 and 54 of the insulator so as to extend beyond the inside end of the cylindrical portion 52, a gasket 70 of oil and heat resistant material being disposed over the outer end of the tube 62 and against the flange 68, where it seats in an end depression 72 in the end of the insulator 48. Over the inside end of the tube 62 there is disposed a rigid insulating washer 74 that rests against the end of the cylindrical portion 52 and engages at its periphery the inside wall 76 of the insulator ring 60. The insulator 74 is of such rigidity as to hold the end of the tube 62 centrally of the ring 60 and thereby equalize the tension of the final assembly. To 20 secure these parts resiliently in the assembled relation, one or more spring steel dished washers 78 are placed over the end of the tube 62 and pressed forceably against the end of the ring 60 where they are held until the end of the tube 62 is spun over as at 80 or otherwise expanded in a riveting relation to engage and compress the spring washers 78. That procedure somewhat flattens out the dished washers 78 and compresses the gaskets 58 and 70 into fluid tight relation between rigid parts of the assembly, and provides a tubular terminal member extending from end to end of the insulator 48, while insulatingly supporting the terminal member by the end member 16.

The high tension terminal member 22 being secured in this fashion, the end member 16 is placed over the end of the case 10 where the open roll 40 of the end member and the end of the case are secured together as indicated at 38 in Figs. 1 and 1A. The partly closed casing is now ready for reception of the coil parts completing the assembly. The tubular case 10 has an inwardly extending annular rib 82 (Fig. 1) that forms a seat for the end of an outside iron assembly 84, that closely engages the inside of the case 10 and surrounds the coil assembly unit 24.

With the coil casing 10 held in position with the high tension terminal down as shown in Fig. 1, and with one end of the outside iron 84 resting against the rib 82, a tubular spacer 86 is passed over the outside of the porcelain washer 60 and is pressed against the end member 16. Then a winding locator 88 is passed over the end of the core wires 26 remote from the leads 32 and 34 and is moved up against the end of the secondary winding 27. The locator 88 is illustrated in detail in Fig. 4, and is composed of some molded insulating material, fashioned in general triangular form to provide the flat sides 90, connected by rounded corners 92 having the same radius of curvature as the inside surface of the outside iron assembly 84. At the center of the locator 88 there is an aperture 94 that closely fits about the bundle of inside core wires 26. The surface of the locator 88 that is disposed away from the winding 27 has arclike depressions 96 and 98 arranged in pairs and connected by radially extending grooves 100 (Fig. 4). That formation provides arclike ribs 102 extending between each pair of depressions 96 and 98 which form seats adapted to engage one end of the spacer tube 86 as shown in Fig. 1.

The winding assembly 24 assembled with the winding locator 88 on the end of the core wires 26

is now passed within the casing assembly so that the rounded corners 92 engage within and slide along the inside of the outside iron assembly 84, and until the ends of the core wires 26 engage the end of the tubular member at 80, and until the winding locator 88 engages the tubular spacer 86 which presses the spacer 86 against the end member 16. An outside insulator tube 104 is next passed over the winding assembly 24 and pushed down inside of the coil of outside iron 84, so that the end of the tube 104 rests against the smooth side of the rounded corners 92 of the winding locator 88. The tube 104 is a little larger in inside diameter than the outside diameter of the winding assembly so as to provide an annular space 108 between them when they are assembled.

An insulating washer 110 is then passed over the end of the core wires 26 and pushed down against the end of the secondary winding 27 which is followed by a tubular spacer 112 of insulation that engages the washer 110 and surrounds the ends of the core wires 26. Then, there follows a combined core cup and winding locator 114 that engages the end of the core wires 26, tubular spacer 112, outside insulator 104, and outside iron assembly 84.

The locating member 114 (Figs. 1 and 3) is made of molded hard insulating material and comprises a plate portion bounded by arcuate ribs 116 and 118 circumferentially spaced and joined by the flat sides 120. The arcuate side 116 has a notch 122 for receiving the longitudinal seam 12 of the case 10, which prevents relative rotation of the locator and the case. One face of the member 114 is fashioned to include a skirt 123 providing a socket 124 for receiving the core wires 26. The skirt 123 closely surrounds the tubular spacer 112. For strengthening the member 114, struts or radially extending ribs 126 join the outside of the skirt 123 to the plate portion and the ribs at the perimeter of the same.

When assembling the core-cup and winding locator 114 upon the winding assembly, the lead 34 from the winding assembly is passed through an aperture 128 in the member 114, while the lead 32 is adjusted to lie against one of the flats 120, after which the member 114 is placed over the end of the core wires 26 and is pressed down within the casing 10 until the ribs 116 and 118 engage the ends of the outside iron 84 and the tubular insulator 104. Continued pressure of this member forces the entire winding assembly and tubular spacers against the high tension terminal end member 16, where the parts are held in firm and centralized relation by a plurality of stakings or inward dents in the casing 10, as at 130.

The coil assembly is now ready for the top end member 14 supplying the primary terminals 18 and 20. Inasmuch as both of the terminals 18 and 20 are substantially the same, and are similarly supported and insulated, a detailed description of one of them is sufficient. In Fig. 5, there is shown in detail the construction of the terminal 18. The end member 14 supporting the terminals has a pair of apertures 132 and 134 for passing of the terminals 18 and 20 respectively, substantially as shown in Fig. 1. Around the aperture 132, (Figs. 1, 2 and 5) the end member 14 is provided with a ridge 136 concentric with the aperture. Around the aperture 134 (Fig. 1) a lock-plate 138 is concentrically arranged. Both the rib 136 and the lock-plate 138 are incorporated on the outside surface of the end

member 14. Centrally disposed on the inside surface of member 14, there is a terminal plate 140 having square apertures 142 and 144 coincident with the apertures 132 and 134 in the end member 14. The terminal plate 140 has a peripheral flange 146 normal to the body thereof and that extends away from the end member 14, and which is designed to closely fit within the end of the case 10 and to assist in the formation of the seam 36. Before any of the terminals are assembled with the end member 14, the lock plate 138, the terminal plate 140 and end member 14 are secured together in any preferred manner as by spot welding.

The structure of either of the terminals 18 or 20 comprises a tubular member 148 (Fig. 5) having a bore 150 extending therethrough for reception and securing of the leads 32 or 34 as the case may be. Intermediate its length, there is a flange 152 having a peripheral rib 154 for surrounding and retaining a gasket 156 of oil and heat resisting material that closely surrounds the mounting portion 158 of the member 148. There is next placed on the part 158 an insulating washer 160 that is followed by another compressible gasket 162 of oil and heat resistant material. The mounting portion 158 of the terminal is somewhat smaller in diameter than the diameter of the aperture 132, so that when the gasket 162 is centered within the rib 136 and compressed against the end member 14, part of the gasket will be forced into the aperture 132 to insure insulation between the parts. The terminal 18 with this assembly of parts is affixed to the end member 14 by passing the portion 158 through the aperture 132 whereupon a square insulating washer 164 is forced over a knurled part 166. Since the washer is square and fits within the square apertures of the terminal plate 140, the terminal 18 or 20 is prevented from turning relative to its support. The terminal 18 or 20 is secured in place by means of spinning or otherwise turning over the end of the tubular member 148 as at 168, to at least partially compress or flatten out a spring steel dished washer 170 that is disposed against the square insulating washer 164 around the mounting portion 158 of the terminal. By forcefully pressing the parts together when spinning the end at 168, such compressive force is exerted upon the gaskets 156 and 162 as to effect a sealed connection, proof against fluid flow through the end member 14. Both terminals 18 and 20 being thus mounted, the leads 32 and 34 are connected to them by passing bared ends of the leads through the bores 150 where they are soldered as is the usual practice, which also seals the bores 150 of the terminals 18 and 20 against leakage. Then the end member 14 is assembled with the case 10 and the casing members secured in a sealed relation by the rolled joint 36 similar in construction to the rolled joint 38 of Fig. 1A. The coil is then stacked with others in a kettle where it is evacuated and impregnated with a suitable oil or wax, and under a condition of heating to a temperature above the normal operating temperature of the coil. This is accomplished through the single opening to the interior of the coil construction provided by the tubular member 62 forming the conductive core of the high tension terminal. When the impregnation is completed, and while the coil is still at the high temperature, the case 10 is hermetically sealed by driving a plug 172 into the end of the ter-

75 minal tip 64 where it is secured in fluid tight relation by soldering as at 174.

The lock plate 138 is adapted to cooperate with a terminal cover 178 rigidly affixed to the end of a flexible metal tube or arbor 180 for protectively enclosing an electric lead 182 provided with a clip 183 adapted to be connected to the terminal 20. The lead 182 is connected with a lock switch, having a housing to which the armor 180 is attached. When the extension lock switch coil thus provided is installed upon a vehicle the armor 180 is stretched so taut as to prevent such flexing of the armor as would permit relative rotation of the coil and cover 178 that might result in separation of the parts and give access to the electrical connection to the terminal 20. Contributing to this end the terminal cover 178 and the lock plate 138 are joined by a bayonet type of coupling that requires something like 60° relative rotation for coupling and uncoupling. This coupling is described in detail in our copending application Ser. No. 296,905, filed September 28, 1939.

When placed in service, the coil is mounted 25 in the position indicated in Fig. 1, or so that the high tension terminal is down. That is accomplished by means of a mounting bracket or band 176 secured to the case 10 and having apertured lugs for the reception of suitable screw devices.

30 While the embodiment of the present invention as herein disclosed, constitutes a preferred form, it is to be understood that other forms might be adopted, all coming within the scope of the claims which follow.

35 What is claimed is as follows:

1. An oil or wax impregnated ignition coil, comprising in combination, a tubular metallic casing, metallic end members secured to the ends 40 of said tubular casing in sealing relation, an outside iron assembly lining the tubular casing, a coil body having windings, means centralizing the windings with respect to the casing and including winding locators, one at each end of the coil body, means including the winding locators and inward extensions of the tubular casing for holding the windings and outside iron assembly against shifting in the casing, there being circumferential spacing between the coil 45 body and the outside iron assembly for the reception of an impregnant.

2. An oil or wax impregnated ignition coil, comprising in combination, a tubular metallic casing, metallic end members secured to the ends 50 of said tubular casing in sealing relation, an outside iron assembly lining the tubular casing, said casing having an inward extension near one end of the said assembly, a winding assembly within the casing and circumferentially spaced from the iron assembly, winding locators disposed at each end of the winding assembly, and means spacing the winding locators from the end members including inward extensions at the other end of the tubular case.

3. An oil or wax impregnated ignition coil, comprising in combination, a tubular metallic casing, metallic end members secured to the ends of said tubular casing in sealing relation, an outside iron assembly lining the tubular casing, said casing having an inward extension near one end thereof for supporting one end of the said assembly, a winding assembly within the casing and circumferentially spaced from the iron assembly, winding locators disposed at each 70 end of the winding assembly, a tubular spacer

disposed between one of the end members and one of the winding locators, and means forcing the winding assembly and the iron assembly against that end member including inward extensions of the case abutting the other winding locator.

4. In an oil or wax impregnated ignition coil, comprising, a tubular metallic casing, and metallic end members secured to the ends of said tubular casing in sealing relation, with a coil body including windings and a core inclosed within the casing, and wherein said core extends at each end beyond the windings, the combination comprising winding locators spaced from the end members of the casing and disposed about each end of the core and supported by the side-walls of the casing for equally spacing the coil body with respect to the casing and means disposed between each of the winding locators and the end members for locating the coil body longitudinally of the casing.

5. The combination set forth in claim 4 in which one of the winding locators comprises a cup engaging one end of the core and is held in place by inward extensions of the tubular case.

6. The combination set forth in claim 4 in which the means engaging the locators includes a tubular spacer centrally disposed with respect to the tubular casing and pressing at one end against one of the end members.

7. The combination set forth in claim 4 in which one of the winding locators has a recessed surface providing arclike ribs concentric to the core, and in which the means spacing the locator from the end member is a tubular spacer one end of which rests upon said ribs of the locator, whereby fluid flow is possible from inside to outside of the tubular spacer.
